US00D986777S

(12) **United States Design Patent** (10) **Patent No.:** **US D986,777 S**
Li (45) **Date of Patent:** **** May 23, 2023**

(54) **E-BIKE**

(71) Applicant: **Shenzhen Xingtú Innovation Technology Co., Ltd**, Shenzhen (CN)

(72) Inventor: **William Li**, Shenzhen (CN)

(**) Term: **15 Years**

(21) Appl. No.: **29/882,684**

(22) Filed: **Jan. 17, 2023**

(51) LOC (14) Cl. **12-03**

(52) U.S. Cl.

USPC **D12/111**

(58) **Field of Classification Search**

USPC D12/110, 111; D21/412, 414, 419, 423,
D21/424, 425, 426, 427, 428, 431, 432,
D21/433, 434, 435

(57) **CLAIM**

The ornamental design for an E-bike, as shown and described.

DESCRIPTION

FIG. 1 is a front, right and top perspective view of an E-bike showing my new design;

FIG. 2 is a front, left and top perspective view thereof;

FIG. 3 is a right view thereof;

FIG. 4 is a left view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged view of a portion labeled as 9 on FIG. 1;

FIG. 10 is an enlarged view of a portion labeled as 10 on FIG. 1;

FIG. 11 is an enlarged view of a portion labeled as 11 on FIG. 1;

FIG. 12 is an enlarged view of a portion labeled as 12 on FIG. 2;

FIG. 13 is an enlarged view of a portion labeled as 13 on FIG. 2; and,

FIG. 14 is an enlarged view of a portion labeled as 14 on FIG. 2.

1 Claim, 14 Drawing Sheets
